UNITED STATES PATENT OFFICE

154,609

DESIGN FOR A TELEVISION TUBE HOUSING AND SUPPORT THEREFOR

Johan C. Kromhout, Forest Hills, N. Y., assignor
to Sylvania Electric Products Inc., a corpora-
tion of Massachusetts

Application May 10, 1947, Serial No. 138,974

Term of patent 14 years

(Cl. D26—14)

To all whom it may concern:

Be it known that I, Johan C. Kromhout, a citizen of the United States of America, residing at Forest Hills, in the county of Queens, in the State of New York, have invented a new, original, and ornamental Design for a Television Tube Housing and Support Therefor, of which the following is a specification, reference being had to the accompanying drawings, forming a part thereof, in which:

Fig. 1 is a plan view of the television tube housing and support therefor, showing my new design;

Fig. 2 is a front elevation;

Fig. 3 is a side elevation of the rotatable and pivotably hinged housing in which the tube housing is shown as being tilted slightly downward and directed to the side.

Fig. 4 is a side elevation of the tube housing and support therefor, as shown in Fig. 2.

The dotted lines shown in the drawings are for illustrative purposes only.

What I claim is:

The ornamental design for a television tube housing and support therefor as shown and described.

JOHAN C. KROMHOUT.
